(57) **CLAIM**

The ornamental design for a stand for photographic or cinematographic cameras, as shown and described.

DESCRIPTION

FIG. 1 is a front perspective view of a stand for photographic or cinematographic cameras.

FIG. 2 is a right side view of the stand for photographic or cinematographic cameras.

FIG. 3 is a left side view of the stand for photographic or cinematographic cameras.

FIG. 4 is a top view of the stand for photographic or cinematographic cameras.

FIG. 5 is a bottom view of the stand for photographic or cinematographic cameras.

FIG. 6 is a front view of the stand for photographic or cinematographic cameras; and,

FIG. 7 is a rear view of the stand for photographic or cinematographic cameras.

The broken lines in the drawings show portions of the article that form no part of the claimed design.

1 Claim, 6 Drawing Sheets
